UNITED STATES PATENT OFFICE.

STANLEY A. JAROSKI, OF HOLYOKE, MASSACHUSETTS.

COMBINATION CONTAINER.

1,411,437.

Specification of Letters Patent. Patented Apr. 4, 1922.

Application filed December 27, 1920. Serial No. 433,469.

To all whom it may concern:

Be it known that I, STANLEY A. JAROSKI, a citizen of Poland, residing at Holyoke, in the county of Hampden and State of Massachusetts, have invented certain new and useful Improvements in Combination Containers, of which the following is a specification.

The main object of this invention is the provision of a combination container for toilet use, which may be carried about at will and which will at all times furnish the user with a number of toilet utensils or articles as may be desired.

15 The above and other objects will become apparent in the description below, in which like-named characters of reference refer to like-named parts in the drawings.

Referring briefly to the drawings, Fig. 1 is 20 a side elevational view of my device, partly in section.

Fig. 2 is a front elevational view of the same with the mirror containing plate removed.

25 Fig. 3 is a perspective view of said mirror containing plate per se.

Fig. 4 is a perspective view of the entire device, partly in section, with various parts exposed.

30 Referring now in detail to the drawings, the numeral 1 represents the handle of my device, to which is secured, integral therewith, the body 2. Said body 2 is hollowed on one side to provide a relatively large com-

35 partment 2^a, and on the other side to provide a relatively small compartment 3^a, the latter having a cover 3 hingedly attached at 4 to said body.

40 A channel-like compartment 5 is provided in the handle 1, extending into the compartment 2^a, and therein a comb 6 is adapted to be retained. At the inner end of said compartment a spring 7 is secured, the purpose of said spring consisting in urging the comb 45 outward at all times. A cover 8 is hingedly attached at 9 to the end of said compartment at the end of the handle 1, and a ridge 10 surrounds the mouth of the compartment 5, said cover being adapted to fit about said 50 ridge. One edge 11 of said ridge is inclined

as shown, and a spring clip 12, secured to said cover at 13, is adapted to resiliently engage said inclined edge when the cover is closed so as to retain said cover in said closed position.

55 The compartment 2^a is provided with a removable cover 14 having spring fingers 15 adapted to engage the edges 19 of said compartment. A mirror 16 is provided on the inner side of said cover. Within the compartment 2^a a number of parallel brush-holding members 17 are rotatably mounted in racks 18. When the cover 14 is in place, said members 17 are in the positions shown in Fig. 2, and, when the cover has been removed, said members may be rotated so as to bring the brush elements in position at right-angles to the body 2, whereby the device may be used as a brush.

60 The compartment 3^a may be used for holding various small articles such as, for instance, a nail file, a sewing needle, or the like. On the handle 1 a member 20 made of strong wire and bent into the form shown, is pivotally attached at 21, and a coiled 65 spring 22 normally urges said member against the handle. This member may be used as a bottle opener.

65 Thus it is apparent that I have provided a compact combination container, which may 70 be carried about at will and will at all times furnish the user with the necessary articles which are carried therein.

I claim:

A toilet implement comprising a hollow 85 flat body and narrow handle of uniform thickness therewith, said handle having a longitudinal recess extending from its outer end into the chamber of the body, a cap 90 hinged at one of its narrow sides to cover the end of said handle, an extension formed with said handle for supporting and guiding said cap when closed, a spring carried by said cap engageable with said extension and a flat spring at the bottom of the handle recess 95 adapted to partially expel an article entered therein when said cap is in an open position.

In witness whereof I affix my signature.

STANLEY A. JAROSKI.
